UNITED STATES PATENT OFFICE.

REUBEN E. SAFFOLD, OF ROCHESTER, NEW YORK.

SHOE-POLISHING DEVICE.

No. 833,003.

Specification of Letters Patent.

Patented Oct. 9, 1906.

Application filed June 23, 1905. Serial No. 266,651.

To all whom it may concern:

Be it known that I, REUBEN E. SAFFOLD, a citizen of the United States, residing at Rochester, in the county of Monroe and State of New York, have invented certain new and useful Improvements in Shoe-Polishing Devices; and I do hereby declare the following to be a full, clear, and exact description of the invention, such as will enable others skilled in the art to which it appertains to make and use the same.

My invention relates to devices for polishing shoes, and has for its object to furnish a brush-like device which can be readily and easily held by an operator and any degree of pressure or friction desired applied to the shoe to produce a high degree of polish thereon.

The invention consists in certain features of construction, which will be fully disclosed in the following specification and claims.

In the accompanying drawings, which form part of this specification, Figure 1 represents a side elevation of my invention; Fig. 2, a vertical longitudinal section; Fig. 3, an inverted plan view of the adjustable supporting-lug, the polishing member being omitted; and Fig. 4, an end view of the same.

Reference being had to the drawings and the designating characters thereon, the numeral 1 indicates the back or base, which may be made of wood or sheet metal and is provided with grooves 2 in the edges thereof for the thumb and fingers of a hand to seize and hold the brush rigidly and securely. On the under side of the back and at each end thereof is a lug or bracket 3, having bisected arms 4 for supporting the polishing member 5 and holding it out of engagement with the under side of the back 1.

The arms are bisected to admit of readily inserting and removing the member 5 through the opening 5'. The polishing member is made of fabric—such as canvas, Turkish toweling, or other coarse fabric having a soft body—and is preferably endless, so that as one portion becomes worn or filled

with the polish used it may be adjusted on the arms of the lugs and a fresh unsoiled portion presented for use.

The polishing member is resilient under 50 pressure, and tension is applied thereto to keep it taut or stretched on the brush by adjusting one of the lugs 3, which is provided with slots 6, through which the screws 7 are inserted, and a screw 8, supported in a lug 9 55 and engaging a nut 10 on the lug 3. The lug 9 is secured on one end of the back by screws 11 11. The lug 3 at the opposite end of the brush is secured to the back 1 by screws 12.

Having thus fully described my invention, 60 what I claim is—

1. A shoe-polishing device provided with an endless flexible polishing member, a fixed and a movable support for said member and means for adjusting said movable support 65 longitudinally and applying tension to the polishing member.

2. A shoe-polishing device provided with a rigid back or base, a flexible polishing member, and lugs having arms thereon for supporting said member out of engagement with said base, and means for adjusting one of said lugs longitudinally.

3. A shoe-polishing device provided with a rigid back or base, an endless flexible polishing member, lugs for supporting said member, and means for adjusting one of said lugs longitudinally.

4. A shoe-polishing device provided with an endless polishing member, lugs having bisected arms for supporting said member, and provided with an opening between the adjacent ends of said arms, and means for adjusting one of said lugs for applying tension to the polishing member.

In testimony whereof I affix my signature in presence of two witnesses.

REUBEN E. SAFFOLD.
